DISTRESS SIGNAL

Abraham Hargreaves, Toronto, Ontario, Canada

Application January 5, 1942, Serial No. 425,604

6 Claims. (Cl. 116—18)

My invention relates to marine signalling devices and has for its paramount object the production of an improved visual signal for a life-boat or like craft whereby a light is displayed to solicit aid for those in distress. More particularly, my invention concerns certain improvements in apparatus for displaying a distress signal by rotating a light casing supported at a suitable elevation above a lifeboat by means of a telescopic standard carried by a base in the nature of a receptacle adapted to contain the operating mechanism and a source of gas for producing the light.

A distinctive feature of construction is that the telescopic standard and the light casing are devised to be removed from the receptacle and the driving mechanism therein so that they may be stored in a compartment forming a part of the receptacle, in order to occupy a minimum of space and provide for compactness.

The invention has for a further object the provision of an apparatus by which a light beam may be flashed on and off while it is revolving about an axis so that signals may issue in code such as are transmitted by the "Morse code." By the adoption of a code signal, the invention may be utilized for war-time purposes. When a vessel is sunk during a state of war and those on board take to the lifeboats it is eminently desirable that a distress signal should be conveyed in code in order that the enemy may not be able to understand the message and thus be posted of the location of survivors which might lead to their capture or destruction. It is also highly desirable that the code of the S O S signal be changed from time to time with a view to minimizing the hazard of the enemy becoming acquainted with it.

Hence my invention further contemplates a mechanism for signalling in code and which can be changed or revised for securing different combinations of component signals. By this arrangement, a given code can be rendered available for an interval of days or other period of time as between those in authority and then changed for a further period and so on as occasion or necessity dictates.

The invention produces a serviceable and practical apparatus which is inexpensive to manufacture.

A practical embodiment of the apparatus is depicted in the accompanying drawing in which

Fig. 1 is a vertical sectional view displaying the device as assembled ready for use.

Fig. 2 is a cross section on line 2—2 thereof 55

showing the cabinet or receptacle which constitutes the base.

Fig. 3 is a front view of the lamp and the mechanism for flashing the signals.

Fig. 4 is a plan view of a stationary plate which carries a circular series of wiper fingers that actuate a shutter of the signal mechanism.

Fig. 5 is a detail showing in full one of the wiper fingers in lowered position, the raised position being indicated in dash lines.

Like numerals of reference denote similar parts in each figure of the drawing.

In carrying out the invention I provide a cabinet or receptacle generally denoted at 7, which is divided by a wall 8 into a lower compartment 9 and an upper compartment 10, both accessible by a lid 11, see Fig. 2. The cabinet serves as a base for the lamp as hereinafter more fully explained, and is ordinarily stowed in a lifeboat as part of the accoutrement thereof. Should occasion require its use, it is attached to a suitable part of the hull of the lifeboat, for which purpose an approved attachment device may be employed, which attachment device is not shown since it may be of standard construction.

Wall 8 carries a non-removable gear and bearing assembly which may by way of example but not of limitation be composed of the bearing 13 attached to said wall as at 14 and journaling the hub 15 of a gear 16 for rotation about a vertical axis. The lower end face of the bearing provides a shoulder for preventing upward displacement of the gear, while an anti-friction thrust bearing 17 precludes downward displacement. The gear is operable by motive power such as that which is capable of being supplied by a suitable spring motor indicated at 18. The spring 19 of the motor is intended to be wound by a key 20, as customary. The drive is effected through the intermediary of appropriate gearing 21 for reducing speed so that the gear 16 may only turn at a moderate rate.

The bore of the gear 16 accommodates the lower member 22 of a tubular standard rising therefrom and supplied with an upper member 23 for telescoping therein. A fastening element 24 serves to secure the lower member to the gear so that it may rotate therewith as a unit and also be detached therefrom. The upper member 23 is fitted with a catch 25 of known type by which it may be held in the extended condition shown in Fig. 1. It will be understood that the catch, which is pivoted at 26, may be depressed to enable the upper member to be telescoped in the lower member. Any known expedient may

be resorted to for keying the upper member to turn with the lower member. For example, the upper member may be fitted with a pin 27 slidable in a slot 28 extending lengthwise of the lower member.

The standard carries a light casing 29 which is mounted by means of a casting 30 rigid with said casing and having a bore which is a running fit on the head end of the upper member 23. The casting is seated on an annulus 31 rigid with said upper member and slotted to receive a locking bar 32 carried pivotally by the casting, as at 33. When the locking bar is swung down to engage the slot of the annulus, the light casing is thereby fastened to the standard and must turn with it. On the other hand, when the locking bar is raised out of engagement with this slot the light casing is free to turn independently of the standard. Normally, the locking bar is in its engaged position as depicted in Fig. 1.

Within the light casing is a burner 33 having a stem 34 loosely mounted by means of a collar 35 in the head of the upper member 23 so that it may remain stationary while the light casing revolves. Said stem is attached to a flexible tube 36 extending freely through the standard and connected to a tank 37 containing a supply of acetylene gas. The tank is secured in the compartment 9 and the delivery line 36 is valve-controlled as at 38. By this construction the burner and the delivery line do not turn as the standard is driven. The delivery line, however, by reason of its flexibility does not interfere with the telescoping of the members 22 and 23 for storage purposes and can be readily detached.

The light casing has a suitable reflector, as at 39, and a lens 40 arranged for throwing a beam of light through an apertured front wall 41 at an upward angle. The front wall is supplied with a horizontally disposed guideway 42 for a shutter 43 slideable to and away from the lens and normally disposed clear of the same. The shutter is actuated by a mechanism comprising a link 44 pivoted to it at 45 and likewise connected to a lever 46 pivoted at 47 to the light casing and having a depending end 47' disposed to engage and ride over a circular series of non-rotatable fingers 48 mounted on a plate 49. Plate 49 is shouldered loosely on the casting 30 so that it may remain stationary in the turning of the light casing, and for the purpose of holding it against movement any suitable expedient may be employed such as a pair of telescopic rods 50 and 51, extending upwardly from the cabinet with the lower one, 51, detachably mounted on the wall 8 such as by a socket.

As detailed in Fig. 5, each of the fingers 48 is pivotally supported, as at 52, on the plate 49 by a post 53 so that it may be swung down from the vertical position illustrated in Fig. 3 to the horizontal position depicted in Fig. 5 in a direction counter to that in which the lever 46 is carried around by rotation of the light casing. A stop face 54 engages a shoulder on the post when the finger is swung to an erect position so that the finger may not turn backwardly when contacted by the lever-end 47'. A flat spring 55 serves to retain the finger in either its erect or lowered position. As the lever rides over a finger, a movement is imparted to it sufficient to close the shutter over the lens and thus momentarily block the light. A spring 56 returns the lever.

Operation

Assuming that the apparatus is assembled, as

shown in the drawing, it will be evident that on setting the motor 18 in operation the gearing 21 will rotate the gear 16 and thus drive the standard together with the light casing which will 5 show a light through the lens when the burner is lit. This light will be flashed on and off as the shutter is operated by the lever 46 successively engaging the raised fingers 48. The number of movements imparted to the shutter in a complete turn will of course depend on the number of fingers raised, since those that are not raised will clear the lever and not make wiping contact with it. When one finger is in an inoperative position the time interval between the successive flashes caused by the adjacent two fingers is doubled. A suitable number of fingers may be employed to provide for a wide variation of signals in code form or otherwise. The fingers are set by hand prior to operation of the light casing by the motor.

The motor will ordinarily be relied upon to drive the light casing, and therefore the locking bar 32 will be in its engaged position. The disengagement of this locking permits the light casing to be rotated independently of the motor drive through the standard. The advantage of this is that it may be found expedient to provide the light casing with some sort of a windmill for emergency rotation. The tank will furnish a supply of gas sufficient for a number of hours.

For storage purposes, the standard and the telescopic rods 50, 51 are collapsed and detached from the cabinet, the member 22 of the standard being removed by loosening the fastening element 35 and pulling it out of the bore of gear 16. The standard and the telescopic rods 50, 51 and also the light casing are then packed in the compartment 10.

While the invention has been disclosed in one practical form it will be understood that such modifications and changes may be resorted to as come within the spirit and scope of the claimed structure.

What I claim is:

1. In a distress signal, a lamp rotatable about an axis and having an aperture for emitting a beam of light, a shutter for the aperture movable between a non-screening and a screening position, an actuator for the shutter mounted on the lamp and having an element projecting parallel to the lamp axis, a circular series of fingers about the lamp axis disposed in the path of said element of the actuator for contact therewith to effect operation of said actuator, and a stationary member supporting the fingers.

2. In a distress signal, a lamp rotatable about an axis and having an aperture for emitting a beam of light, a shutter for the aperture movable between a non-screening and a screening position, an actuator for the shutter mounted on the lamp and having an element projecting parallel to the lamp axis, and a circular series of displaceable fingers about the lamp axis disposed in the path of said element of the actuator for operable engagement therewith in the rotation of the lamp to effect operation of said actuator.

3. In a distress signal, a rotary light casing having a light source therein and an aperture for emitting a beam of light, a guideway at the aperture, a shutter slideable in the guideway between a non-screening and a screening position, a lever connected to the shutter and pivoted on the casing, said lever having a depending end, and a series of fingers circularly arranged around the axis of the casing in the path of travel of

the depending end of the lever for wiping contact therewith, said fingers being severally shiftable out of the path of travel of said depending end of the lever.

4. In a distress signal, a rotary light casing having a light source therein and an aperture for emitting a beam of light, a guideway at the aperture, a shutter slidable in the guideway between a non-screening and a screening position, a lever connected to the shutter and pivoted on the casing, a stationary plate encircling the axis of rotation of the casing, a series of fingers circularly arranged around the axis of the casing in the path of travel of the depending end of the lever, and means pivotally mounting the fingers on the plate aforesaid and resiliently retaining them in an obstructing position with respect to said depending end of the lever.

5. In a distress signal, a base, a rotatable standard thereon, a light casing carried by the standard, said light casing having a light emitting aperture in its wall portion, a shutter slidable horizontally on the apertured wall portion for blocking the light, a radially extending plate journaled independent of the standard, a series of actuators circularly arranged on the plate about the axis of the standard, means on the light casing for engaging the actuators to operate the shutter, and a member extending from the base alongside of the standard to retain the plate against rotation.

6. An apparatus as set forth in claim 5 and in which the standard and the member for retaining the plate against rotation are of telescopic construction and detachable from the base.

ABRAHAM HARGREAVES.
